SOUND RECORDING

John H. McLeod and Walter K. Grimwood,
Rochester, N. Y., assignors to Eastman Kodak
Company, Rochester, N. Y., a corporation of
New Jersey

Application October 13, 1937, Serial No. 168,779

3 Claims. (Cl. 179—100.3)

This invention relates to sound recording and particularly to push-pull sound-on-film recording.

It is an object of the invention to provide a so-called noiseless or class B push-pull recording system using variable area.

It is a particular object to provide a toed-in variable area class B push-pull sound record and a method of producing such a record.

10 It is a further object of the invention to provide a ribbon type light valve of extremely simple construction capable of producing the above-mentioned sound record.

According to the invention, a ribbon type light valve consisting of a single ribbon in the usual magnetic field and an aperture at least as wide as the ribbon, is connected to an input circuit carrying the signal to be recorded. An optical system including a source of light and suitable spherical and cylindrical lenses projects a shadow image of this ribbon to a sensitive film on which the record is to be made. The optical system must be such that the edges of this shadow image are sharp (i. e., the image must be longitudinally sharp) and the image should exactly fill the sound track area for zero input signal. Furthermore, a mask exactly overshadowing the remainder of the film is placed as nearly as possible in the plane of the ribbon or of a real image thereof, such as at the film itself or at any intermediate image. Positioning the mask near an intermediate image is preferable since otherwise, the mask would tend to interfere with the vibration of the ribbon or the motion of the film when placed near enough to either to insure exact and sharp masking.

For zero input signal, no light reaches the film since the shadows of the ribbon and that of the mask are exactly supplementary to each other. On the introduction of a modulation, the positive half of each cycle causes the ribbon to move to one side permitting light to pass between the mask and the other side of the ribbon or an image thereof. Similarly, the negative half of each cycle causes the ribbon to move the other way from the zero position and on the film there is thus recorded a negative sound track of uniform maximum width which is alternately reduced from the two sides in accordance with the negative and positive amplitudes respectively.

The usual advantages of class B push-pull recording as discussed in a copending application, Serial Number 168,777, patented June 6, 1939, No. 2,161,369, filed concurrently herewith by

55 McLeod, one of the present inventors, and

Morse, are thus obtained in a unique and convenient manner requiring relatively simple light valves and in the preferable embodiment, a simple uni-axial optical system. The positive sound track printed from the above negative sound track consists of a succession of transparent areas having widths varying in accordance with the input signal and alternately, according to the positive and negative halves of each cycle, bordering on the sides of the area assigned to the sound record. As is the case with all class B push-pull recordings, the positive sound track approaches a maximum density for small input signal.

Other objects and advantages of the invention will be apparent from the following description when read in connection with the accompanying drawing, in which:

Fig. 1 is a schematic drawing of a sound recording system incorporating the invention. 15

Fig. 2 is a plan of the optical system employed in Fig. 1.

Fig. 3 schematically shows a recording system incorporating a preferred embodiment of the invention. 25

Fig. 4 is a plan of the optical system employed in Fig. 3.

Fig. 5 is an elevation of this optical system.

In Fig. 1 an input signal picked up by a microphone 10 is passed through its accompanying amplifier 11 to any suitable input circuit shown as a transformer having a primary 12 and a secondary 13. A ribbon type light valve comprising a ribbon 14 in the usual magnetic field (not shown in Fig. 1 but portions 16 of the pole pieces appear in Fig. 2) is connected across the input circuit. An optical system comprising a source of light 20, spherical lenses 21 and 23, and a cylindrical lens 26 projects a sharp shadow image of the ribbon 14 onto a film 30 having the usual picture area 31. Any suitable optical system may be used provided the shadow image of the ribbon 14 exactly fills the area 32 provided therefore on the film. That is, the edges of the ribbon 14 must be exactly imaged by the lens system shown as the spherical lens 23 and the cylindrical lens 26 along the lines 33 and 34. This is clearly shown in Fig. 2.

The height of this shadow image is limited by a mask 24 having a slit 25, preferably positioned near the lens 23 and arranged so that the cylindrical lens 26 projects a sharp image of this slit 25 onto the film. This is the usual expedient for providing sharp resolution.

According to the invention, a mask 22, shown

55

approximately in the plane of the ribbon 14 is positioned to exactly overshadow the remainder of the film not covered by the shadow image of the ribbon 14 itself. As discussed in the general 5 case above, this mask 22 may be in the plane of the ribbon 14, the plane of the film or in the plane of any intermediate image of this ribbon 14.

The preferred embodiment of the invention wherein the mask is in the plane of an intermediate image is shown in Fig. 3, wherein a lens system shown as a simple positive lens 27 projects an aerial image of the ribbon 14 at the position indicated by the broken lines 14'. The mask 22 is replaced by a mask 22' which together with 10 the shadow image 14' just cuts out all the light when no input signal is present.

Figs. 4 and 5 indicate clearly how the lens 27 forms an exact image 14' of the ribbon 14 in the plane of the mask 22' and further how this image 20 is projected by the lens 23 onto the film 30. How the cylindrical lens 26 and slit 25 perform their function of exactly determining the height of the recording beam as it strikes the film 30 is also clearly shown.

25 In Figs. 1 and 3, the single aperture in the magnet of the light valve is indicated by broken line 15. In Figs. 2, 4, and 5, this aperture is shown by indicating the magnet 16 in cross section. The mounting and tensioning of a ribbon in the magnetic field is well known in the art and need not be discussed in detail here. The aperture 15 must be at least as wide as the ribbon 4. In fact, it is conceivable that it could be arranged to be exactly the same width and to act as the 30 mask for this ribbon 14, but from a practical point of view it is not convenient to do so and hence the only arrangements shown include the introduction of an extra mask 22 or 22'.

40 Having thus described our invention and the manner in which it may be practiced, we wish to point out that it is not limited to the specific embodiments shown, but is of the scope of the appended claims.

What we claim and desire to secure by Letters Patent of the United States is:

1. A variable area push-pull sound-on-film recording system comprising an input circuit carrying the signal to be recorded, a single ribbon, single aperture light valve across the input circuit, a sensitive film having a portion adapted to receive the sound record and an optical system including a source of light, for projecting a longitudinally sharp shadow image of the ribbon 10 onto the film, said image exactly covering said portion for zero input signal and stationary masking means in a plane other than that of the ribbon exactly overshadowing the remainder of the film. 15

2. A variable area push-pull sound-on-film recording system comprising an input circuit carrying the signal to be recorded, a single ribbon light valve having an aperture at least as wide as the ribbon which is connected across the 20 input circuit and an optical system including a source of light for projecting a longitudinally sharp shadow image of the ribbon in the plane adapted to be occupied by the sensitive recording medium and stationary masking means for 25 limiting the width of said plane to exactly the width of said shadow image, whereby, at zero input signal said shadow image and the shadow of said masking means are exactly supplementary. 30

3. A variable area push-pull sound-on-film recording system comprising an input circuit for carrying the signal to be recorded, a single ribbon single aperture light valve across the input circuit and an optical system including a source of light for illuminating the valve, lenses 35 for projecting a longitudinally sharp intermediate shadow image of the ribbon between the valve and the plane for the film and for reimaging this shadow image in the film plane and stationary masking means in the plane of the intermediate 40 image exactly supplementing its width at zero input signal only.

JOHN H. MCLEOD.
